UNITED STATES PATENT OFFICE.

GEORGE B. HOWELL, OF PHILADELPHIA, PENNSYLVANIA.

WATER-CLOSET.

SPECIFICATION forming part of Letters Patent No. 430,855, dated June 24, 1890.

Application filed August 5, 1889. Serial No. 319,713. (No model.)

To all whom it may concern:

Be it known that I, GEORGE B. HOWELL, a citizen of the United States, and a resident of Philadelphia, Pennsylvania, have invented 5 certain Improvements in Water-Closets, of which the following is a specification.

My invention consists of an improvement in the water-closet shown and described in the patent of Thomas Kennedy, No. 376,002, dated January 3, 1888, the object of my invention being to supply both the bowl and siphon-jet of such a water-closet by means of one pipe, and to dispense with the necessity for trapping this pipe in the service box 15 or reservoir of the closet. These objects I attain in the manner hereinafter set forth, reference being had to the accompanying drawings, in which—

Figure 1 is a side view of sufficient of a 20 water-closet to illustrate my invention. Fig. 2 is an end view of the same, looking in the direction of the arrow, Fig. 1; and Fig. 3 is a sectional view of part of the closet.

The water-closet described in the before- 25 mentioned patent of Kennedy consisted of a bowl having a siphoned discharge-pipe, in which the siphon action was set up by the operation of a jet of water entering the upper end of the long leg of the siphon and 30 producing a partial vacuum therein, so as to cause the flow of water from the short leg of the siphon into the long leg. The patented device, however, was provided with two pipes 35 leading to the service-box, one of these pipes supplying the water for flushing the bowl of the closet and the other supplying the jet, and as in said closet there was no trap between the soil-pipe and the long leg of the siphon it became necessary to trap the jet- 40 pipe in the service box or reservoir, in order to prevent the escape of sewer-gas into the room or apartment containing the closet.

In carrying out my invention I use a single supply-pipe *a*, which communicates with 45 one end of a loop *b*, the opposite end of which forms the jet-pipe *d* for the long leg of the siphon, the loop and jet-pipe being preferably formed of the same material as the bowl and siphon-pipe of the closet, and

the loop lying closely to the opposite sides 50 of the siphon-pipe and passing from one side of the same to the other beneath the neck formed where the short leg *B* of the siphon joins the long leg *D* of the same. From the upper or inlet portion of the loop *b* a 55 branch *f* extends to the bowl *A*, this branch communicating with the space behind the flushing-rim *g* of the bowl, and also, by preference, communicating directly with the bowl through a drip-passage *i*. When water is 60 first permitted to flow through the pipe *a*, therefore, a portion of it passes through the loop *b* and supplies the jet-pipe *d*, and another portion passes through the branch *f* into the flushing-rim of the bowl, so that 65 the latter is flushed simultaneously with the starting of the siphon by the jet. During the latter part of the flow the volume of water is not more than enough to fill the branch *f*, so that it seeks the readiest means 70 of escape by passing through said branch into the bowl, the action of the jet ceasing, so as to permit the latter part of the flow to fill the trap at the bottom of the bowl. When the flow ceases, the loop *b* is filled 75 with water up to the level of the bottom of the branch *f*, so that it forms an effective trap or seal for preventing gas from the soil-pipe from gaining access to and passing into the room or apartment through the supply- 80 pipe *a* or rim *g* of the bowl.

Having thus described my invention, I claim and desire to secure by Letters Patent—

1. The combination of the bowl and its 85 siphon discharge-pipe with a single water-supply pipe leading from the reservoir and terminating in a trapped loop discharging into the upper end of the long leg of the siphon, said loop having a branch located 90 below the upper bend of the trap and extending to the flushing-ring of the bowl, substantially as specified.

2. The combination of the bowl and its 95 siphon discharge-pipe with a single water-supply pipe leading from the reservoir and terminating in a trapped loop fitting snugly to the siphon discharge-pipe on each side

and crossing beneath the neck of said pipe, | said trapped loop discharging into the top
of the long leg of the siphon, and having be- | of the long leg of the siphon, and having be-
low the upper bend a branch extending to | low the upper bend a branch extending to
5 the flushing-ring of the bowl, substantially | the flushing-ring of the bowl, substantially
as specified.

In testimony whereof I have signed my

name to this specification in the presence of
two subscribing witnesses.

GEO. B. HOWELL.
